UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

HEEL-BREASTING MACHINE.

Application filed October 11, 1916, Serial No. 125,102. Renewed November 4, 1921. Serial No. 512,955.

To all whom it may concern:

Be it known that I, LOUIS A. CASGRAIN, a citizen of the United States, residing at Beverly, in the county of Essex and State 5 of Massachusetts, have invented certain Improvements in Heel-Breasting Machines, of which the following description, in connection with the accompanying drawings, is a specification, like reference characters on the 10 drawings indicating like parts in the several figures.

This invention relates to machines for breasting the heels of boots and shoes.

The power breasting machines now in 15 commercial use are for the most part of the type in which the stroke of the knife is varied in accordance with the height of the last and the thickness of the sole at the shank, this stroke being controlled by a stop 20 which engages the shank of the shoe and is connected with mechanism for disconnecting the knife from its operating mechanism when the knife has reached the shank of 25 the sole at the completion of the heel breasting operation.

Although machines of this type are extensively and successfully used there is in 30 the use of them always a possibility that the knife arresting mechanism may get out of adjustment or become worn, so that under some working conditions the knife may overthrow and cause injury to the shank or else be stopped before the cut is finished.

It has been recognized that a fixed stop 35 may be provided for the shoe shank and the knife given a constant stroke such that its edge will reach the plane of the shoe engaging face of the stop, the shoe being held firmly against the stop during the operation 40 of the knife. In the construction of such machines it has been difficult to devise a shank stop mechanism which would not be in the way of the shoe during its introduction into and removal from the machine and 45 which would accurately and adequately sustain the pressure of the shoe against it under all conditions.

The general object of this invention is to 50 provide an improved heel breasting machine which will be free from the faults or defects of prior machines and which will perform the breasting operation in a better, more

accurate and expeditious manner. More specifically stated, an object of this invention is to devise new and improved mechanism which will automatically position the stop relatively to the shank after the introduction of the shoe into the machine and will properly locate and hold the stop during the operation. Preferably the mechanism will 55 also automatically remove the stop from proximity to the shoe before the shoe is removed from the machine.

With this object in view, a feature of the invention consists in a vertically movable 60 stop, and means for automatically bringing the stop into operative relation as an incident to the movement of the shoe when brought into position to be operated upon. As herein shown, the stop is arranged to be 65 moved by gravity into operative position and is held elevated by means which is arranged to be released by movement of the shoe support toward the machine.

Another feature of the invention consists 70 in the combination with means for raising the shoe against the stop, of means for holding the stop against upward movement which becomes effective automatically to 75 sustain the pressure of the shoe against the stop. As herein shown, the stop holding means comprises a member which is introduced between the stop and a vertically rigid portion of the machine, movement of the 80 member being effected preferably by a preliminary movement of the starting treadle before the machine starts. Preferably the holding member comprises a wedge which 85 may be adjusted to vary the effective thickness of the holding member for varying the 90 vertical position of the stop.

Another feature of the invention consists 95 in means for automatically releasing the stop after the breasting operation and moving it away from the shoe so that it will not interfere with the removal of the shoe from the machine. As shown herein, the stop holding member is removed automatically from above the stop member and the stop is automatically connected to the knife 100 operating mechanism and lifted away from the shoe.

When heels are breasted in the usual manner by a knife which moves in the direction

of the height of the heel or, if the heel is attached to a shoe, from the tread face of the heel toward the shank it is frequently found that the knife does not produce a smooth cut on the heel breast but that the heel has a "stepped" appearance, the upper edge of each lift projecting beyond the lower edge of the lift above it. This formation of the heel breast is particularly noticeable when leather heels are being breasted and is due to the fact that the resistance of the chip to the passage of the knife increases as the knife approaches the lower edge of the lift, by reason of the pressure of the bevel of the knife edge against the resisting chip which causes the knife to spring or draw in toward the body of the heel. When the knife passes through a given lift this pressure is suddenly released and the knife springs out and begins its cut on the next lift in a plane slightly in front of the plane where the cut on the lift above was finished. In order to finish a rough heel breast thus made, considerable scouring is necessary, whereas it is highly desirable that the breast be as smooth as possible when it leaves the breasting machine so that little or no scouring or buffing will be needed.

Another object of this invention, therefore, is to provide means for producing upon the heel a smooth breast face before it leaves the breasting machine. With this object in view, another important feature of the invention consists in means for trimming the heel breast, for instance, by the removal of a thick roughing chip therefrom and automatic means operating to effect a finishing cut from substantially the entire heel breast to eliminate any roughness resulting from the previous or rough trimming operation. In the illustrated machine an organization is shown comprising a reciprocating breasting knife, means for operating it repeatedly, and means for effecting relative movement of the knife and heel in the direction of the length of the heel between successive operations of the knife. In the construction herein shown, the knife has a two stroke cycle, and means is provided for moving the knife rearwardly of the heel a predetermined distance after the first stroke and before the second stroke. This construction enables a roughing cut to be first made by the removal of a thick chip and then a finishing cut by the removal of a thin chip or shaving. Preferably the knife is arranged to reciprocate in the direction of the height of the heel, that is, when the heel is attached to a shoe, in the direction from the tread face of the heel toward the shank, and as herein shown the knife carrier is moved relatively to the heel about a center remote from and preferably below the heel between the strokes of each cycle.

Since it is a usual practice to breast the heels of shoes while the shoes are still upon their lasts, it is important to provide mechanism for upholding a shoe on its last which will accommodate itself to lasts of varying height without special attention upon the part of the operator and without his making any time-consuming adjustments. Accordingly a feature of the invention consists in an initially compressible last support upon which the shoe is yieldingly sustained so that a last of any height may be located in the machine by depressing the last and allowing it to rise against the means for positioning the shoe vertically, for example the stop above referred to, with means, preferably becoming effective upon power operation of the machine, for rendering the support unyielding and applying pressure thereto to hold the shoe against the stop. As shown, the pressure applying means acts irrespectively of the height of the last to apply uniform upward pressure to the last support, the last support being locked in whatever vertical position it may be made to assume by introduction of a last of any height and then having a predetermined upward pressure applied thereto.

It is important that the shoe be upheld by relatively light but substantial and constant pressure up to the time when the cut of the knife begins in order that the operator may have as much time as possible to position the shoe with respect to the positioning devices which determine its relation to the knife, and it is important when the shoe is so positioned and the cut of the knife is about to begin that the shoe be upheld substantially rigidly to resist the cutting action of the knife. Accordingly, another feature of the invention consists in the combination with breasting means and a stop against which the shoe is located, of means for effecting an upward pressure of the shoe against the stop and then applying an increased pressure during the breasting operation. Preferably a preliminary pressure is first applied which, as shown, is constant and then a final pressure of predetermined amount is applied which is preferably sufficient to sustain the shoe substantially rigidly during the operation of the knife, the pressure being, however, sufficiently yielding to prevent excessive pressure upon the shoe or undue strain upon the machine parts. As shown herein the jack post is normally sustained by a light spring and is backed up at its lower end by a liquid which is controlled by a normally open valve, the valve being closed by a spring when the jack is raised and maintaining a constant preliminary pressure on the liquid as the jack is raised against the resistance of the shank stop and other positioning devices until the jack approaches the upper limit of its move-

ment, whereupon additional or final pressure is applied to the valve to render the liquid support to the jack substantially unyielding. It will be observed that, by the features of the invention above explained, a last of any height may be inserted in the machine by depression of the last support against a light spring, the last being raised and measured when downward pressure is relieved and its vertical position determined by the stop. When the machine starts, the last support is raised by means which acts uniformly upon the last support, whatever may be the position it has been made to assume by insertion of the last and hence irrespectively of the height of the last.

Furthermore, the machine is preferably so adjusted that in making the roughing cut on the heel this first chip will be substantially but not quite severed and means is provided to increase the upward pressure of the shoe during the second cut, this cut being made with less resistance on the part of the heel because of the thinness of the chip and the heel being more forcibly upheld, the knife will cut completely through the heel and sever the chip. The stop and connecting parts of the machine will also yield slightly under the increased pressure and allow the knife therefore to cut a little deeper. Another feature of the invention consists, accordingly, in the combination of means for removing successive chips from the heel of a shoe, and a substantially fixed stop for positioning the shoe relatively to the limit of the knife stroke, of means for increasing the pressure of the shoe against the stop between the removal of the successive chips from the heel. If the knife upon its first reciprocation is allowed to cut through the heel there is danger that it will slightly mar or scratch the shank of the shoe, which scratch will become more noticeable after another chip is removed by the second operation of the knife. By the above construction, however, this danger is avoided.

These and other features of the invention will appear more fully from the following description when read in connection with the accompanying drawings and will be pointed out in the appended claims.

Fig. 1 is an elevation of the left hand side of the machine;

Fig. 2 is a similar view, on an enlarged scale, of the upper portion of the machine;

Fig. 3 is a detail in perspective of the wedge member for holding the stop against upward movement;

Fig. 4 is a sectional view of part of the stop operating mechanism;

Fig. 5 is a front elevation of the upper portion of the machine;

Fig. 6 is a sectional view of the base portion of the machine taken on a plane extending from front to rear of the machine;

Fig. 7 is a detail, in rear elevation, of the mechanism shown in Fig. 6;

Fig. 8 is a sectional view of the base portion of the machine on a plane extending transversely of the machine;

Fig. 9 is a top plan view of the mechanism for positioning the heel relatively to the knife;

Fig. 10 is a side view, partly in section, of the mechanism shown in Fig. 9.

Fig. 11 is a detail in perspective of the mechanism shown in Figs. 9 and 10;

Fig. 12 is a plan view, partly in section, of the clutch mechanism and part of the cam controlled mechanism for operating the machine; and

Fig. 13 is a front view, partly in section, of the mechanism shown in Fig. 12.

In Fig. 1 of the drawings, which is a side view of the machine, the front being to the right, the frame is indicated by the numeral 2. In the base of the frame is mounted a drive shaft 4 which extends from front to rear of the machine and is connected to a power driven pulley 6 by a two revolution clutch, the trip arm of which is shown at 10 in this figure. The shaft 4 is connected by a two to one gear 12, 14 with a cam shaft 16 parallel with the shaft 4 and carrying two cam blocks 18, 20. The operating treadle for tripping the clutch to start the machine is shown at 21.

Referring to Fig. 6, which shows the base portion of the machine partly in median section, it will be seen that the forward end of the shaft 4 carries a crank 22 which is connected to a cross-head 24 by a connecting rod 26. A rearward projection 25 of the cross-head 24 when near the lower limit of its movement engages a buffer spring 27 seated in a socket in the machine frame. The spring absorbs the momentum of the heavy downwardly moving parts and assists in restoring them to the raised position.

In Fig. 8, which is a section at right angles to Fig. 6, the cross-head 24 is shown as fixed to rods 28, 28 which are guided for up and down reciprocating movement in trunnion blocks 30, the trunnions 32 of which are journaled in the machine frame. The trunnions 32 permit a forward and backward swinging movement of the rods 28, and cross-head 24 for a purpose to be explained. The upper ends of the rods 28, as shown in Fig. 5, have fixed to them a cross-head 34 which carries the breasting knife of the machine indicated at 36. The knife is held in the cross-head by clamping mechanism which is substantially similar to that shown and described in Letters Patent of

the United States No. 1,289,652, granted December 31, 1918, on my application. A hand wheel 38 serves to rotate a right and left worm 40 which rotates worm wheels 42. The shafts of the worm wheels 42 are pro-

vided with pinions which engage racks on laterally movable knife clamping members to move them toward and from the knife as in the prior construction.

5 Above the cross-head 34 the rods 28 pass through guides 50. The guides 50 have trunnions 52 (Fig. 2) journaled in a yoke 54 which is pivoted at 56 to the machine frame and has a rearwardly extending arm 58 connected by a rod 60 to a lever 62 (Fig. 13). The lever 62 has a fixed pivot on a shaft 64 at one end and at the other end carries a roll 66 which engages a cam path in the front face of the cam block 18. Movement 15 of the yoke 54 upwardly about the pivot 56 by reason of the connections 58, 60, 62 to the cam block 18 will slightly shift the position of the guide 50 rearwardly of the machine, the trunnions 32 permitting such movement 20 of the guide 50 and rods 28. Rearward movement of the rods 28, of course, carries rearwardly the cross-head 34 and knife 36 so that if the knife is reciprocated while the rods 28 are in forward position and then 25 the rods are moved rearwardly and the knife reciprocated, a second chip will be removed by the knife. This chip is preferably very thin, for instance 1/32 or 1/64 of an inch thick. The trunnions 32 are so far 30 below the knife that the slight swinging of the rods 28, about them does not alter materially the angular direction of the cutting movement of the knife.

The mechanism for supporting the shoe 35 will now be described, being best shown in Figs. 6 and 8. This mechanism comprises a hollow jack post 70 connected by a universal joint comprising pivots 71, 73 to a lever 72 having a fixed pivot on the shaft 64 at one end and at the other end carrying a cam roll which engages a cam path on the cam block 20. In the jack post 70 is a rod 74 arranged to move freely longitudinally and normally upheld by a relatively light spring 76 (Fig. 6) connected at one end to the post 70 and at the other to a pin which passes through a slot in the post 70 and is fixed in the rod 74. The rod 74 at its lower end is a piston fit in 40 a chamber 78 containing a liquid, for example oil, and having a lateral passage for the liquid closed by a valve 80 (Fig. 8). When the valve 80 is open the rod 74 will move freely up and down to permit the 45 insertion into the machine of a last of any height and when the valve is closed the rod 74 will be supported against depression to a degree depending upon the force with which the valve is held to its seat. To hold 50 the valve seated, two springs 82, 84 are provided, the spring 82 acting directly upon the valve and the spring 84 acting upon the upper end of a valve stem 86. The valve stem 86 has a block 90 pinned to its 55 upper end which, when the post 70 is low-

ered, engages a projection 92 from the machine frame and causes the valve to open. When the post 70 is swung to and fro about the pivot 71 the block 90 slides on the projection 92 (Fig. 6), the engaged surfaces being grooved to prevent lateral play and the upper surface of the projection 92 being curved from 71 as a center. The block 90 passes through an opening in a cylinder 94 which has a rearward projection pivoted at 96 to a rearward projection on the post 70 (Fig. 6). Projecting forwardly from the cylinder 94 is an arm 97 (Fig. 8) which carries an adjusting screw 98 engaging a flat surface 100 formed on a member 101 adjustably secured to the frame by bolts 102. Within the cylinder 94 is the spring 84 which bears on a plate 104 attached to the block 90 and a screw plug 106 bearing on the other end of the spring 84 serves as means for adjusting its tension. It will be apparent from Fig. 8 that as the lever 72 is raised by the cam 20, the jack post 70 will be lifted, raising the block 90 from the projection 92 and allowing the valve 80 to be closed by the relatively light spring 82. As the jack post and rod 74 continue to rise against resistance of means comprising a fixed stop, to be described, for holding the shoe against upward movement relatively to the knife, a predetermined pressure upon the shoe is maintained. When, however, the upper limit of movement of the jack is approached, the screw 98 engages the surface 100 and the tension of the spring 84 is brought to bear upon the valve 80 to increase the upward pressure on the shoe, this pressure being applied to any last irrespectively of its height since the last was positioned in the machine by depressing the rod 74 before closing of either of the valves. The combined tension of the springs 82 and 84 is preferably such that they hold the valve closed under any usual working conditions and the post is therefore substantially positively locked against depression.

After the first cut is made on the heel it is desirable to increase the pressure of the shoe against the stop. This is effected by the formation of the jack raising cam 20 shown at 23 in Fig. 8 comprising a slight change in the radius of curvature of the cam path whereby when this point in the cycle is reached the lever 72 will be raised slightly either before or during the second cut of the knife. The effect of this is to crowd the shoe harder against the fixed stop and by reason of the resulting increased strain upon the parts slightly raising the shoe so that when the knife descends the second time in the cycle it will cut more deeply than it did upon its first reciprocation. By this construction the machine may be so adjusted that the knife, upon its first 130

descent in the cycle, will cut almost through the heel to the shank but not quite far enough to detach the chip from the heel and so that after the upward pressure upon the jack is increased the second cut of the knife will completely sever both chips from the heel. By this adjustment all danger of the knife cutting through the heel and marking the shank upon its first operation is obviated. If the knife be allowed to cut completely through the heel upon the first stroke there is danger that the knife edge will make a slight mark upon the sole, which mark would be rendered more obvious by the removal of the second chip from the heel.

The mechanism which holds the shoe against the upward movement of the jack and positions the shoe vertically relatively to the knife for the breasting cut will now be described. Referring to Figs. 2, 3, 4 and 5 of the drawing; 110 is a gage or stop which engages the shank of the shoe and is supported at times to resist the upward pressure of the jack during the breasting operation and is automatically moved out of the way after that operation is completed to permit convenient withdrawal of the shoe from the machine and the introduction of the succeeding shoe. The stop 110 is mounted to slide vertically in a part 112 pivoted at 114 to the machine frame and affording a vertically rigid support for the stop. Between the upper end of the stop 110 and the post 112 is a wedge member comprising relatively adjustable parts 116, 118 (Figs. 4 and 5). A stop 117 (Fig. 4) is provided to limit movement of the part 116 of the wedge member always to the same extent, and a screw 120 is provided to vary the relative position of the parts 116, 118 and hence to vary the effective thickness of the wedge. When the wedge is in the position shown in Figs. 2 and 4 it forms a rigid abutment for the end of the stop 110, being backed up by the part 112 which, as stated, is mounted on the machine frame so as to be rigid against upward pressure. The stop 110, therefore, under these conditions, provides a rigid abutment against which the shoe is clamped by the jack for the operation of the knife 36. The vertical operative position of the stop 110 may be varied by adjusting the parts 116, 118 of the wedge member by the screw 120 so that the shank contacting face of the stop 110 may be made to correspond with the lower limit of the knife stroke, the knife being first set in its holder so that its edge will be approximately in the plane of the shank engaging face of the stop when the knife is at its lower limit of its stroke. In front of the knife is a member 122 which is clamped in a fixed position in the holder 34 with the knife, and on the member 122 is a screw 124 having a milled nut 126 which

overlies the upper end of the knife and forms an abutment to position the knife and help take the cutting thrust. The nut 126 may be adjusted on the screw 124 to accommodate knives of different lengths and the varying lengths of the same knife as it is shortened by grinding.

Near the end of the cycle of the machine the wedge member 116, 118 is withdrawn and the stop 110 is raised in its slide to carry it above the shoe heel so that the shoe may be readily withdrawn from the machine. To effect this, a rock shaft 130 is mounted in an arm 132 extending forwardly from the part 112. The rock shaft has an arm 134 loosely connected to the part 116 of the wedge member by a pin 136 passing through the member and lying in slots 138 formed in the end of the arm 134 which is bifurcated. Another arm 140 on the rock shaft 130 is connected to one end of a lever 144 fulcrumed at 142 to the machine frame and connected at its opposite end to an operating rod 146. The rod 146 extends downwardly to the base of the machine where it is yieldingly connected to an arm 148 (Fig. 8). To provide this yielding connection, the lower end of the rod 146 is slotted at 149 and a pin on the arm 148 passes through the slot and is connected by a spring 147 with an adjustable collar 145 on the rod 146. The arm 148 extends laterally from a rock shaft 150 by which the clutch setting mechanism, to be described, is operated. The yielding connection permits movement of the arm 148 to trip the clutch after further movement of the wedge member is prevented by engagement of the stop 117 with the part 112. Depression of the treadle 21 to set the clutch rocks the shaft 150 in a counter-clockwise direction causing the arm 148 to pull on the rod 146 which moves the forward end of the lever 144 and the arm 140 upwardly, causing the arm 134 to push the wedge member 116, 118 into operative position. Before the knife returns on its second reciprocation, the shaft 150 is rocked back to its initial position and the wedge is withdrawn to permit the stop 110 to be raised with the knife as will be further explained. The part 118 of the wedge member has rearwardly extending guides 119 (Fig. 3) which engage transverse guideways in the part 112 and a space is provided between the guides 119 sufficient to permit the stop 110 to be raised between them when the wedge member is in its forward position, its wedge portion being then forward of the path of movement of the stop. The loose connection afforded by the pin 136 and slots 138 permits rectilinear transverse movement of the guides 119 notwithstanding the curvilinear movement of the end of the arm 134.

The mechanism for raising the stop 110 with the knife when the knife returns after

the second or finishing cut is as follows. In the rear face of the stop 110 (Fig. 4) is a notch 158 with which the suitably formed forward end of a slide 160 mounted on the knife carrier or cross head 34 cooperates to lift the stop. The slide 160, however, must be prevented from engaging the notch 158 during the upward movement of the knife after the first movement of the knife for removing the thick chip from the heel breast, and the slide 160 must be withdrawn after a shoe is inserted in the machine to permit the stop to drop into operative position. For this purpose another slide 162 is arranged over the slide 160 and between projections on the two slides respectively is a spring 164 which moves the slide 160 toward the stop 110 when permitted to do so by the release of a catch 165 on the slide 162 which engages a notch in the slide 160 for retraction of the two slides together by movement of the slide 162 through connection with the jack. This connection comprises a rod 166 connected to the slide 162 at one end and at the other to one arm 170 (Figs. 1 and 4) of a bell-crank having a fixed pivot at 168. The other arm 171 of the bell-crank is connected by a rod 172 to one arm 174 (Fig. 6) of a bell-crank having a fixed pivot at 176 and having on its other arm 178 a pin 180 lying in a slot 182 formed in the end of a link 184 which is pivoted to a rearward projection 186 from the jack.

In Figs. 2 and 4 the parts are shown in the positions they occupy when the machine is just starting to effect the first breeding cut, the knife being about to descend for the first time in the cycle. The slides 160, 162 have been retracted while locked together by the catch 165, the movement having been effected by the rearward movement of the jack which has caused the forward end of the slot 182 (Fig. 6) to push on the pin 180 and through the connection described to pull on the rod 166. Rearward movement of the slide 160 has disengaged its forward end from the notch 158 and permitted the stop 110 to drop into engagement with the shoe, and the wedge member 116, 118 has been inserted above the stop to sustain the pressure of the jack post which has been raised. During the first operation of the knife to remove the first or thick chip from the breast the slide 160 is held retracted by the catch 165. When the knife carrier is moved rearwardly prior to the second cut for removing the thin or finishing chip from the heel by rocking of the lever 58, a projection 190 (Fig. 2) on the lever engages an upstanding portion 192 of the catch 165, causing it to release the slide 160 which is urged forwardly by the spring 164 into engagement with the stop 110. During the second descent of the knife the end of the slide 160 is moved downwardly past the notch 158 and on

its return engages the notch and raises the stop 110 out of engagement with the shoe, the wedge member 116, 118 having, of course, been withdrawn before the upward movement of the knife carrier occurs by movement of the rock shaft 150 into position to throw out the clutch. When the jack is swung outwardly for removal of the shoe, the inner end of the slot 182 engages the pin 180 and through the connections described pushes the slide 162 forwardly relatively to the slide 160 until the catch 165 engages the notch in the slide 160, and when the jack is moved rearwardly with the next shoe the forward end of the slot 182 engages the pin 180 and retracts both slides together to permit the stop 110 to drop again into operative position.

It is convenient to be able to move the stop 110 and its attendant mechanism from in front of the knife so that the knife may readily be removed or adjusted. When the forward end of the lever 144 is depressed so that its pivotal connection with the arm 140 is axially in line with the pivot 114 of the arm 132, the part 112, stop 110, arms 134, 132, etc., will swing outwardly about 114 as a center against a spring 181 which is connected between a pin 183 on the frame and the rock shaft 130. When these parts are swung up to the limit of their movement the longitudinal axis of the spring lies above the pivot 114 and holds the parts in raised position.

Co-operating with the stop 110 in supporting the shoe is a tread plate 200 (Fig. 1) mounted on a frame 201 which is pivoted at 202 to the forward end of a lever 203 fulcrumed on the machine frame at 204. To the lever 203 between its ends is pivoted a tubular member 206 to which is connected an operating rod 208 which telescopes into it and has a slot in its lower end portion which engages a pin 209 (Fig. 13) on a cam operated lever 210 fulcrumed at 204 and having at its opposite end a cam roll 212 engaging a cam path 214 in the rear face of the cam block 18. A spring 216 is connected between the pin 209 and an adjustable block 218 (Fig. 6) clamped to the rod 208 and acts to hold the pin normally against the upper end of the slot. As the machine starts, the cam roll 212 is moved toward the center 16 of the cam block (Fig. 3) depressing the lever 210 and pulling downwardly upon the rod 208 through the spring 216, yielding pressure being thereby applied to the tread plate 200 to a degree depending upon the tension of the spring 216. To vary the initial position of the tread plate 200 so that heels of varying heights may be positioned beneath it, mechanism best shown in Fig. 8 is provided. The operating rod 208 is provided on the portion which lies in the tubular member 206 with ratchet teeth 220 which are

engaged by similar teeth formed on a pawl block 222 mounted in the member 206 and held toward the rod 208 by a spring 224. The block may be released from the teeth 220 by pulling on a handle 226 and when so released the member 206 is moved upwardly relatively to the rod 208 by a spring 228. To set the plate for a heel higher than that for which the heel has been previously used, the block 222 is released, allowing the tread plate 200 to rise to the limit of its movement, the heel is then positioned beneath the plate, and the plate depressed against the heel, the pawl block 222 sliding downwardly 15 over the ratchet teeth 220 and adjusting the length of the operative rod 208 and member 206 to the new height of heel, no further adjustment of the plate being necessary until heels of a substantially different height are 20 to be operated upon. To adjust the plate for heels lower than those previously breasted, it is of course necessary only to depress the plate into contact with the heel after the shoe has been introduced beneath it.

25 On the lower face of the plate 200 are arranged shoe-positioning fingers 230 (Figs. 9, 10 and 11) by which the forward and lateral positions of the heel are determined. The fingers 230 are pivoted at 232 to a slide 234 mounted in the frame 201 and are connected at 236 by interengaging toothed segments for equal and opposite movement. The fingers are urged toward each other by a spring 237. On the slide 234 (Fig. 10) is 30 an upstanding lug 238 having threaded engagement with a threaded tube 240. The rear end of the tube carries a flange 242 guided in a housing 244 on the frame 201. The rear end of the housing is closed by a 35 screw plug 247 against which a spring 246 located in the tube 240 abuts. By turning the tube 240 the slide 234 and fingers 230 may be adjusted longitudinally of the shoe and the slide and fingers may be moved 40 rearwardly against the spring 246. For convenience in turning the tube 240, a thumb head 248 is provided on a laterally extending rod 250 rotatably mounted in the frame 201 and carrying a spiral gear 252 which meshes 45 with a similar gear 253 on the tube 240. The fingers 230 have hooked ends which engage the breast edge of the top lift and position the shoe longitudinally relatively to the knife, and the thumb head 248 and connected 50 mechanism afford means for adjusting the fingers longitudinally of the shoe to vary the amount of material removed by the first cut of the knife.

55 Before the descent of the knife it is necessary to separate the hooked ends of the fingers 230 to release them from the heel and then to retract them from the path of the knife. To effect this, wedge members 254 are provided which engage inclined faces 255 on the inner edges of the fingers.

The wedge members 254 are threaded to a right and left hand screw 256 which is rotatably mounted on upstanding brackets 258 between which is rotatably mounted on the screw 256 a depending T-shaped member 260 the lateral projections of which engage the wedge members 254 and swing them rearwardly as best shown in Fig. 11. An adjusting screw 261 is threaded through the member 260 and is connected to the gear 253 by a connection 263 such that the screw 256 will be rotated with the tube 240. Arranged to press rearwardly on the screw 261 is an arm 262 on a rock shaft 264 mounted in upstanding brackets 266 and having an operating arm 268 connected (Fig. 1) by a link 269 to an arm 270 on a rock shaft 272. Another arm 274 on the rock shaft 272 is connected by a rod 276 to a rearwardly extending bracket 278 on the lever 210 (Fig. 12), the lower end of the rod 276 being slotted (Fig. 13) to provide a lost motion connection with the lever. Immediately after the machine starts and before the knife reaches the fingers 230, the lever 210 exerts a pull on the rod 276 and through the connections described swings the arm 262 rearwardly against the screw 261, moving the T-shaped member 260 against the wedge members 254 which act on the inclined faces 255 on the fingers first to separate the fingers against the spring 237. After separation of the fingers to free their hooked ends from the heel breast, lugs 257 on the members 254 engage faces on the fingers 230 which are perpendicular to the longitudinal axis of the shoe and move the fingers together rearwardly against the spring 246 beyond the plane of operation of the knife. Rotation of the tube 240 to adjust the finger longitudinally of the shoe also turns the screw 261 through the connection 263 and correspondingly adjusts the T-shaped member 260 and wedge members 254 to maintain their relation to the inclined faces of the fingers constant. The fingers should remain in open and retracted position until the shoe is removed from the machine and accordingly a latch is provided to hold the rod 276 depressed until the jack is swung outwardly. Referring to Figs. 1, 6 and 7, it will be seen that the rod 276 carries a block 280 adjustably clamped to it. A latch 282 is pivoted to the arm 178 to swing forwardly against a spring 284 but not rearwardly beyond the position shown in Fig. 6, where the latch is in engagement with the top face of the block 280 and is holding the rod 276 depressed and the fingers retracted. When the jack is drawn forward for removal of the shoe, the connection 184 pulls the arm 178 forwardly and moves the latch 282 off of the block 280 permitting the rod 276 to rise in response to the spring 246 which moves the fingers for-

wardly for their work positioning function. When the jack is moved rearwardly with the next shoe the latch 282 hits the side of the block 280 and stops while the arm 178 continues to swing rearwardly, tensioning the spring 284. When the rod 276 is again depressed the latch 282 snaps over the block 280 and holds the rod down until the jack is moved forwardly again.

10 On the shaft 4 (Fig. 13) is the disk 300 of a Horton clutch, from over the stop lug 302 of which a lateral projection 303 (Fig. 12) of the stop arm 10 has just been removed to permit the clutch to take hold 15 and start the machine. The lateral projection 303 carries the usual spring member 304 to engage the lug 302 and lessen the shock of stopping. The arm 10 is fixed to the rock shaft 150 and is urged toward the 20 clutch disk by a spring 306. Mounted loosely on the shaft 150 is a member 308 having an arm 310 which may be raised by an underlying projection 312 of the treadle 21. To the member 308 above the shaft 150 25 is pivoted at 314 an angular member comprising a dog 316 and an arm 318. Fixed to the shaft 150 by a clamp screw 320 is a member 322 which carries a notched plate 324 the notch of which is engaged by the dog 316 when the arm 310 is raised by the treadle and causes rotation of the shaft 150 to move the arm 10 away from the clutch disk 300. The shaft 150 also has fixed to it by a clamp screw 326 a member 328 which 30 carries a brake shoe 330 having a rocking bearing at 332 thereon and having its upper end urged toward upward projection 334 on the member 328 by a spring 336. The parts are so arranged that rocking of 35 the shaft 150 and the member 328 will release the brake shoe from the edge of the cam block 18. The member 328 has an arm 340 extending to the right (Fig. 12) and carrying a screw 342 which is engaged by an 40 underlying lug 344 on the lever 62 so that while the lever 62 is held raised by its cam it is impossible for the shaft 150 to rock back into stopping position or for the brake 45 330 to be applied. After the lug 302 has 50 passed the stop projection 303 on its second revolution a projection 346 lifts the arm 318 of the dog 316 disengaging it from the notched plate 324 and allowing the rock shaft 150 to rock under the influence of the 55 spring 306 and carry the stop arm 10 into clutch releasing position when permitted to do so by the cam controlled movement of the lever 62. The brake 330 is also carried into 60 operative position but is not completely set until a certain portion 348 of the periphery of the cam block 18 reaches the brake at the end of its revolution, the cam being somewhat eccentric and this portion being farthest from the center to bind on the 65 brake and stop the machine. The clock-

wise rocking movement of the shaft 150 takes place early enough in the cycle to cause the arm 148 to operate through the rod 146 to remove the wedge member 116, 118 from over the stop 110 and permit it 70 to be raised by the second upward movement of the cross-head 34 at the end of the cycle.

In the operation of the machine, the shoe support being swung outwardly about the 75 pivot 71, the operator places a shoe upon the shoe support, the toe being upheld by the usual toe rest, as shown, if desired. He then swings the shoe and support toward the machine at the same time slightly depressing the post 74 and shoe against the light spring 76 to bring the top lift below the plane of the hooked ends of the fingers 230 beneath the tread plate 201. When the heel is under the plate and between the fingers, the shoe is released and raised by the spring 76 against the plate. It is then drawn forward until the top lift engages the fingers 230 and the heel is positioned thereby in proper relation to the knife. As 80 the shoe rest approaches its inner position the latch 160 is withdrawn through the connections 166, 170, 172, 174, 178, 184, 186, as described, and the stop 110 drops into contact with the shoe shank. 85

The operator next depresses the treadle 21 which rocks the shaft 150 and swings downwardly the outer end of the arm 148 which through the connections 146, 144, 130, 134 moves the wedge member 116 into position 100 above the stop 110 to hold it against upward movement as the jack is raised. Further movement of the treadle trips the clutch and the shafts 4 and 16 begin to rotate. The cam 20 on the shaft 16 operates the lever 72 105 to lift the jack first yieldingly as the liquid passes through the valve 80 held by the relatively light tension of the spring 82 and finally lifts the jack substantially positively as the screw 98 engages the surface 100 110 and the tension of the spring 84 becomes effective with that of the spring 82 to hold the valve 80 closed. The knife has begun its descent but before it reaches the fingers 230 they are withdrawn in the manner described by a pull on the rod 276 effected by the cam path on the rear face of the cam block 18 through the lever 210 and are locked in retracted position by the latch 282 which engages above the block 280 (Fig. 6). The 115 knife now passes through the heel substantially to the shank practically severing a thick chip from the heel, the wedge member 116 and knife adjusting screw 124 having, of course, been first adjusted to produce this 120 effect. The knife now returns and immediately begins a second descent. In the meantime the lever 62 is operated by its cam path 68 on the cam block 18 and pulls downwardly on the rod 60. This movement 125 130

moves the upper guides 50 of the sliding rods 28, 28 toward the rear, the lower guides 30 rocking on the trunnions 32. During this movement of the arm 38 the projection 190 5 has engaged the tail 192 of the catch 168 and released the slide 160 which moves forward against the stop 110. The knife upon its second descent removes a thin shaving from the heel and the pressure of the shoe 10 upon the stop 110 having been increased by the movement of the lever 72 effected by the formation 23 on the cam path in the cam block 20, the knife cuts a little deeper on the second cut than on the first and severs cleanly 15 the chips from the heel. Before the knife starts to return, the rock shaft 150 is permitted to turn to bring the stop 10 in position to throw out the clutch and also to move the arm 148 to retract the wedge member 20 116, 118 from above the stop 110 which upon the return of the knife carrier is picked up by the slide 160 and is raised out of the way of the shoe. At the same time the jack is lowered. The machine now stops and the 25 shoe is free to be swung outwardly away from the machine. As the shoe is swung away from the machine for removal the end of the slot 182 strikes the pin 180, removing the catch 282 from above the block 280 thereby 30 permitting the positioning fingers 230 to move forward and close ready to position the top lift of the next heel.

Having fully described my invention, I claim as new and desire to secure by United States Letters Patent:

1. In a machine of the class described, means for supporting a heel to be breasted, and means acting in the direction of the height of the heel for first removing from 40 the breast of the heel a roughing chip and power driven means operating to effect a finishing cut, said means being constructed and arranged to eliminate from the entire heel breast any roughness resulting from the 45 removal of the roughing chip.

2. In a machine of the class described, means for holding in fixed position a shoe heel to be breasted, means acting in the direction of the height of the heel for 50 breasting the heel, and automatic means for making a similar and finishing cut on the breasted heel.

3. In a machine of the class described, means for holding in fixed position a shoe 55 having a heel to be breasted, means for breasting the heel in a direction from the tread face of the heel toward the shank, and means for automatically repeating the breasting operation on substantially the entire heel breast face.

4. In a machine of the class described, means for supporting a shoe, means including a knife and means for operating the knife in the direction of the height of the 60 heel of the shoe for breasting the heel, means

for relatively moving the shoe and breasting means in the direction of the length of the shoe, and means for again operating the breasting means.

5. In a power operated breasting machine 70 arranged to perform automatically its cycle and stop, a heel support, a breasting knife acting in the direction of the height of the heel, means for operating the knife to breast the heel, means for moving relatively the heel and knife in the direction of the length of the heel a predetermined distance, and means for operating the knife a second time in the same cycle.

6. In an automatic machine constructed 80 and arranged to perform its cycle and stop, a breasting knife, means for operating the knife in the direction of the height of a heel twice in the same cycle, a heel support, and means for relatively moving the knife and heel support after the first operation of the knife and before its second operation.

7. In an automatic machine constructed and arranged to perform its cycle and stop, a support for holding the heel in fixed position, a breasting knife, means for operating the knife in the direction of the height of the heel twice in the same cycle, and means for moving the knife toward the rear of the heel after the first operation of the knife 95 and before the second operation.

8. In a heel breasting machine, a shoe support constructed and arranged to hold the shoe in position for the breasting operation, a knife arranged to operate in a direction 100 from the tread face of the heel toward the shoe, means for operating the knife first to remove a chip from the heel, means for shifting the knife and shoe relatively in the direction of the length of the heel, means for 105 operating the knife a second time, and means for stopping the machine after the second operation of the knife.

9. In a heel breasting machine, a shoe support constructed and arranged to hold the shoe in position for the breasting operation, a knife arranged to operate in a direction from the tread face of the heel toward the shank, and means for operating the knife 110 automatically first to remove from the breast 115 of the heel a roughing chip and then operating the knife to remove a finishing chip.

10. In a heel breasting machine, a shoe support constructed and arranged to hold the shoe in position for the breasting operation, a knife arranged to operate in a direction from the tread face of the heel toward the shank, means for operating the knife to remove a thick chip from the heel, and means for relatively moving the shoe and 120 knife and for then operating the knife to remove a thin chip from the heel.

11. In a heel breasting machine, a shoe support constructed and arranged to hold a shoe in position for the breasting operation, 125

a knife arranged to operate in a direction from the tread face of the heel toward the shank, means constructed and arranged to give the knife two reciprocations and stop, 5 and means for moving the knife a predetermined distance toward the rear of the heel between its reciprocations.

12. In a machine of the class described, a vertically fixed stop, power operated means 10 for raising the shoe against the stop at first with yielding pressure and then with substantially positive pressure, and means for breasting the heel of the shoe while thus held positively supported.

13. In a machine of the class described, a fixed stop, a plurality of springs, power operated means for raising the shoe against the stop first with a pressure controlled by one of the springs, and then with a pressure 20 controlled by both of said springs, the joint action of said springs being such as to hold the shoe substantially rigidly against the stop, and means for breasting the heel of the shoe while so held.

14. In a machine of the class described, a fixed stop, a relatively light spring and a relatively heavy spring, power operated means for pressing the shoe against the stop first through the agency of the light spring, 30 means for rendering the heavy spring effective to reinforce the light spring when the shoe is in clamped position against the stop, and means for breasting the heel of the shoe so held.

15. In a heel breasting machine, a shoe support, a breasting knife, a tread plate for engaging the tread face of the heel, power operated means for yieldingly pressing the plate against the heel, and connections from 40 the power operated means to the plate comprising a ratchet and pawl which permit the plate to be depressed into contact with a low heel and constructed and arranged to maintain this adjustment during repeated operating cycles of the machine, the pawl being releasable for adjustment of the plate to a high heel.

16. In a heel breasting machine, a shoe support, a breasting knife, a tread plate, 50 means for operating the plate to force it against the heel including a ratchet and pawl adjustment which is maintained during successive cycles of the machine, and resilient means for raising the plate when 55 the pawl is manually released.

17. In a heel breasting machine, a shoe support, a reciprocating cross head, a knife on said cross head arranged to breast the heel of a shoe on said support, and means 60 to check the momentum of the cross head only when near the lower limit of its stroke and to accelerate its movement during the first part of its upward stroke.

18. In a machine of the class described, 65 the combination of a knife having a fixed

limit of reciprocation, a shoe support movable toward and from the machine, a vertically movable shank stop, means permitting movement of the stop into position to locate the shoe shank at the limit of the knife stroke after the shoe is moved into operative position, means for holding the stop against vertical movement during the breasting operation, and means for moving the stop away from the shoe to permit withdrawal of the support and shoe from the machine.

19. In a machine of the class described, the combination of a knife having a fixed limit of reciprocating movement, a shoe support movable toward and from the machine, a vertically movable shank stop, means operated by movement of the shoe support for permitting the stop to drop upon the shoe shank, means operated by the starting treadle for preventing the stop from being raised beyond the point where its shoe engaging face is at the limit of the knife stroke, means operating when the machine starts for raising the shoe against the stop, and means for then operating the knife to breast the heel.

20. In a machine of the class described, a knife having a stroke the lower limit of which is constant, shoe supporting means movable toward and from operative position under the knife, a vertically movable shank stop normally out of the way of introduction of the shoe in the machine, and automatic means for positioning the stop and holding the shoe against the stop with the face of its shank at the limit of the knife stroke.

21. In a breasting machine, a knife having a two stroke cycle, a shoe support movable toward and from the machine, a vertically movable stop normally raised to permit introduction of the shoe into the machine, means operating before the beginning of the first stroke for permitting movement of the stop into operative position, means for holding the stop against vertical movement, means for pressing the shoe against the stop, and means operating during the second stroke of the knife for releasing the holding means and raising the stop out of contact with the shoe.

22. In a heel breasting machine, the combination of a reciprocating knife, shoe supporting means movable toward and from the knife and movable into and out of position beneath the knife, a breasting stop movable in the same direction as the knife from a position above the shoe, where it will clear the heel in its movement on the support into position beneath the knife, to a position against the shank of the shoe, means to limit return movement of the stop to locate the shank at a predetermined height relatively to the limit of the knife

stroke and means for raising the shoe support to clamp the shoe against the stop when the stop is in its limited position.

23. In a machine of the class described, 5 a reciprocating breasting knife, a stop arranged to drop upon the shoe after its insertion into the machine, means for holding the stop against upward movement, means for raising the shoe against the stop, and 10 means for thereafter operating the knife to breast the heel.

24. In a machine of the class described, a reciprocating breasting knife, a stop arranged to drop upon the shoe after its insertion in the machine, means for holding the stop against upward movement, means for raising the shoe against the stop, means for thereafter operating the knife to breast the heel, and means operated by the knife 20 for removing the stop from the shoe after the breasting operation.

25. In a heel breasting machine, the combination of breasting means, a work support movable toward and from the machine 25 and vertically, a stop, automatic means for causing the stop to be brought into contact with the shoe after the support is moved toward the machine, and means for supporting the stop against movement while 30 the shoe is moved vertically against it and for moving the stop out of the path of the shoe before the supporting means is withdrawn.

26. In a heel breasting machine, a shoe 35 support constructed and arranged to hold the shoe in position for the breasting operation, a knife arranged to operate in a direction from the tread face of the heel toward the shank, means for operating the knife 40 to remove one chip from the heel, means for relatively moving the shoe and knife, and means for thereafter operating the knife to remove another chip from the heel.

27. In a breasting machine, a shoe support constructed and arranged to hold the shoe in position for the breasting operation, a knife arranged to operate in a direction from the tread face of the heel toward the shank, means constructed and arranged to 50 give the knife a plurality of reciprocations, and automatic means for moving relatively the shoe and knife a predetermined distance between reciprocations of the knife.

28. In a machine of the class described, a 55 vertically fixed stop, means for raising the shoe against the stop at first with yielding pressure and then with substantially positive pressure, means for breasting the heel of the shoe while thus held by the support, 60 means for moving relatively the breasting means and the heel longitudinally of the heel, means for increasing the pressure of the shoe against the stop, and means for repeating the breasting operation upon the heel.

29. In a machine of the class described, the combination of a knife having a fixed limit of reciprocation, a shoe support movable toward and from the machine and also movable vertically, a vertically movable 70 shank stop, means for positioning the stop to locate the shoe shank at the limit of the knife stroke after the shoe is moved on its support into operative position, means for raising the support to clamp the shoe against 75 the stop, and means for moving the stop away from the shoe to permit withdrawal of the support and the shoe from the machine.

30. In a machine of the class described, the combination of a knife having a fixed 80 limit of reciprocating movement, a shoe support movable toward and from the machine and vertically, a vertically movable shank stop, means operated by movement of the shoe support for permitting the stop to drop 85 upon the shoe shank, a treadle, means operated by the treadle for preventing the stop from being raised beyond the point where its shoe engaging face is at the limit of the knife stroke, power operated means for 90 raising the shoe against the stop, means for operating the knife to breast the heel, means for moving relatively the knife and heel in the direction of the length of the heel, means for increasing the pressure of the shoe 95 against the stop, and means for again operating the knife to remove a second chip from the heel.

31. In a machine of the class described, the combination of a knife having a fixed 100 limit of reciprocating movement, a shoe support movable toward and from the machine and vertically, a vertically movable shank stop, means operated by movement of the shoe support for permitting the stop to drop upon the shoe shank, a treadle, means operated by the treadle for preventing the stop from being raised beyond the point where its shoe 105 engaging face is at the limit of the knife stroke, power operated means for raising the shoe against the stop, means for operating the knife to breast the heel, means for moving relatively the knife and heel in the direction of the length of the heel, and means for again operating the knife to remove a 110 second chip from the heel.

32. A heel breasting machine comprising a reciprocating knife having a stroke the lower limit of which is constant, a work support movable to and from alignment 120 with the knife and movable toward and from the knife in alignment therewith, a stop for the shoe movable in the same direction as the knife into and out of operative position, and automatic means for locating and holding the stop against movement during the breasting operation at such a point that the shank of the shoe will be at the limit of reciprocation of the knife.

33. A heel breasting machine comprising 130

a reciprocating knife, a work support movable to and from alignment with the knife and movable toward and from the knife in alignment therewith, a stop for the shoe movable in the same direction as the knife into and out of operative position, and automatic means independent of the shoe for limiting movement of the stop as the support is moved toward the knife at a point where the shank of the shoe is at the limit of reciprocation of the knife.

34. A heel breasting machine comprising a reciprocating knife having a stroke the lower limit of which is constant, a work support movable to and from alignment with the knife and movable toward and from the knife when in alignment therewith, a stop for the shoe movable in the same direction as the knife into and out of operative position, and means for positively holding the stop against movement during operation of the knife.

35. A heel breasting machine comprising a breasting knife, means for imparting cutting movements thereto, a shoe support movable toward the knife and in the direction opposed to the knife's cutting movement, and a stop arranged to engage the shoe shank for arresting the shoe to determine the depth of cut, said stop being moved automatically toward and from operative position in the same direction as the knife and independently of the shoe.

36. A heel breasting machine comprising a reciprocating knife, a work support movable toward and from the knife, a stop movable in the direction of the knife, and means movable into position above the stop to render the stop fixed during the operation of the knife for arresting movement of the work toward the knife.

37. A heel breasting machine comprising a reciprocating cutting knife, a work support movable toward and from the knife, a stop immovable during operation of the knife for limiting movement of the work toward the knife, and means for moving the stop in the direction of knife movement after the operation of the knife and before movement of the shoe.

38. A heel breasting machine comprising a reciprocating cutting knife, a work support movable toward and from the knife, a stop movable automatically into the path of the work for arresting movement of the work toward the knife, said stop remaining in engagement with the work throughout the operation of the knife, and means for moving the stop out of the way of the work after operation of the knife and before movement of the work.

39. In a heel breasting machine, a knife having a constant stroke, means including a tread plate for clamping a shoe with its shank at the limit of the knife stroke, means

on the tread plate for engaging the corners of the heel breast to determine the longitudinal position of the shoe heel relatively to the knife, and automatic means for operating the knife and clamping means and for withdrawing the positioning means from engagement with the heel.

40. A heel breasting machine having, in combination, a breasting knife having a cutting stroke to a fixed point toward which the shoe is uplifted, automatic means for positioning and clamping the shoe with its shank at said fixed point, and automatic means for operating the knife a plurality of times to remove successive chips from the heel.

41. In an automatic heel breasting machine constructed and arranged to complete its cycle and stop, a breasting knife, means for operating the knife twice in the cycle, a shoe support, means for relatively moving the knife and shoe support after the first operation of the knife and before its second operation, and means for raising the support between the operations of the knife.

42. In a heel breasting machine, a shoe support constructed and arranged to hold the shoe clamped for the breasting operation, a knife arranged to operate in a direction from the tread face of the heel toward the shank of the shoe, means for causing the knife to operate a plurality of times and stop, and means for moving the knife rearwardly of the shoe between its operations.

43. In a heel breasting machine, a shoe support constructed and arranged to hold the shoe clamped for the breasting operation; a knife arranged to operate in a direction from the tread face of the heel toward the shank of the shoe, means for causing the knife to operate a plurality of times and stop, and means for increasing the clamping pressure on the shoe between operations of the knife.

44. In a machine of the class described, a heel support, a reciprocating breasting knife arranged to act in the direction of the height of the heel, and automatic means for reciprocating the knife and for moving relatively the knife and support to cause the knife first to remove a roughing cut and then a finishing cut from the heel breast.

45. In a machine of the class described, the combination of a reciprocating breasting knife, acting from the tread face of the heel toward the shank of the shoe, means for positioning the shoe shank at the limit of the knife stroke, means for pressing the shoe upwardly against the positioning means, and automatic means for increasing the pressure after one operation of the knife to cause the second cut to be made deeper than the first cut.

46. A knife having a fixed limit of recip-

- ocation, a shoe support movable toward and from position under the knife and vertically, a stop, means becoming effective upon movement of the shoe support under 5 the knife for causing vertical movement of the stop against the shank to be effected, a starting treadle, means operated by the starting treadle for limiting return movement of the stop by elevation of the shoe 10 support at a point where the shoe engaging face of the stop is substantially at the limit of the knife stroke, means for elevating the shoe support, and means for locking the support against movement in response to the 15 thrust of the knife during its operation.
47. A heel breasting machine comprising a knife and a shoe support movable toward and from each other, said shoe support being otherwise movable to and from alignment 20 with the knife, a stop movable in the direction in which the knife and support move toward and from each other, means controlled by the movement of the shoe support to and from alignment with the knife for causing 25 the stop to be brought into contact with the shoe, means for holding the stop against upward movement, and means for elevating the shoe support to press the shoe against the stop.
48. In a heel breasting machine, a reciprocating knife, a shank stop against which the shoe is held immovable during operation of the knife upon a heel, means for operating the knife, and means for moving the 30 knife relatively to the heel after the first breasting operation so that upon a second operation of the knife a second cut will be made upon the heel.
49. In a heel breasting machine, a reciprocating knife, a shank stop for positioning a shoe shank at the limit of the knife stroke, means for operating the knife to breast the heel of the shoe, and means for moving relatively the knife and the shoe to cause the 35 knife upon a second operation to make a second cut upon the heel.
50. In a heel breasting machine, means for positioning and holding a shoe, a knife constructed and arranged to cut completely across the entire breast face of the heel of the shoe, and means for moving relatively the shoe holding means and the knife to cause the knife upon a second operation to make another complete cut upon the breast 45 of the heel.
51. In a heel breasting machine, a reciprocating knife, a support for holding a heel with one of its flat faces substantially perpendicular to the direction of reciprocation of the knife, means for operating the knife to cut a chip from another flat face of the heel, and means whereby the operation of the knife on said second face may be repeated.
52. In a heel breasting machine, the combination of breasting means, a shoe support movable toward and from the machine, a shank stop, means for causing the stop to be brought into contact with the shank of the shoe upon movement of the support toward 70 the machine, and means for moving the stop out of the way of the shoe before the shoe is withdrawn from the machine.
53. In a machine of the class described, the combination of a breasting knife, means 75 for positioning the shoe relatively to the knife comprising fingers arranged at each side of the heel and having formations to engage the front edges of the heel and determine its longitudinal position, and means operating 80 during the descent of the knife and independently thereof to separate the fingers for the passage of the knife between them.
54. In a machine of the class described, the combination of a breasting knife, means 85 for positioning the shoe relatively of the knife comprising fingers having hooked ends arranged to embrace the heel and to determine by contact of their hooked ends with the heel breast the longitudinal 90 position of the shoe, and operating means independent of the means for operating the knife for first separating the fingers and then retracting the fingers out of the path of the knife to permit the knife to pass between 95 them.
55. A heel breasting machine comprising a reciprocating knife having a fixed limit of movement toward the shoe, a shoe support movable in the direction of the movement of the knife and movable into and out of operative position beneath the knife, a stop movable toward and from the shoe in the direction of movement of the knife a sufficient distance to clear the heel of a 100 shoe on the support when moved into operative position, means for raising the shoe support, and means for causing the stop to arrest the shoe with its shank at the limit of the knife stroke during the operation of 105 the knife.
56. A heel breasting machine comprising a reciprocating knife the lower limit of movement of which is constant, a work support movable toward and from position under the knife and movable in the direction of the knife movement, a stop movable toward and from the shoe in the direction of movement of the knife, power means for raising the shoe support, and automatic 110 means for causing the stop to arrest the shoe with the shank at the limit of the knife stroke until operation of the knife has been completed and then withdrawing the stop out of the way of the shoe heel to permit 115 movement of the support from beneath the knife.
57. A heel breasting machine comprising a reciprocating knife having a fixed limit of movement toward the shoe, a shoe sup- 120 125 130

port movable in the direction of the movement of the knife, a stop movable toward and from the shoe in the direction of movement of the knife, means for raising the shoe support, and automatic means for causing the stop to arrest the shoe with its shank at the limit of the knife stroke until the operation of the knife has been completed and then withdrawing the stop out of the way of the shoe.

58. A heel breasting machine comprising a reciprocating knife the lower limit of movement of which is constant, a work support movable toward and from position under the knife and movable in the direction of the knife movement, a stop movable toward and from position to arrest the shoe when moved toward the knife, means for raising the shoe support, and means for withdrawing the stop out of the way of the shoe heel to permit movement of the support from beneath the knife.

59. A heel breasting machine comprising a reciprocating knife having a fixed limit of movement toward the shoe, a shoe support movable in the direction of the movement of the knife and movable into and out of operative position beneath the knife, a stop movable toward and from the shoe in the direction of movement of the knife a sufficient distance to clear the heel of a shoe on the support when moved into operative position, means for raising the shoe support, and adjustable means for causing the stop to arrest the shoe when raised by the support at a point where its shank is at the limit of the knife stroke.

60. A heel breasting machine comprising a reciprocating knife the lower limit of movement of which is constant, a work support movable toward and from position under the knife and movable in the direction of the knife movement, a stop movable toward and from the shoe in the direction of movement of the knife, means for raising the shoe support, means for causing the stop to arrest the shoe with the shank at the limit of the knife stroke during operation of the knife, and means for withdrawing the stop out of the way of the shoe heel to permit movement of the support from beneath the knife.

61. In a machine of the class described, the combination of breasting means, a movable shoe support, an abutment against which the shoe is pressed by movement of the support, and means for moving the support including a confined liquid through which pressure is applied to the shoe.

62. In a machine of the class described, the combination of breasting means, a movable shoe support, an abutment against which the shoe is pressed by movement of the support, means for moving the support including a confined liquid through

which pressure is applied to the shoe, and means for controlling the pressure applied through the liquid to the shoe support.

63. In a machine of the class described, the combination of breasting means, a movable shoe support, an abutment against which the shoe is pressed by movement of the support, means for moving the support including a confined liquid through which pressure is applied to the shoe, and means for holding the liquid first under that pressure and later under heavy pressure to transmit first light and then heavy pressure to the work.

64. A machine of the class described having, in combination, breasting means, a movable shoe support and an abutment against which the shoe is pressed by movement of the support, means for moving the shoe support comprising a confined liquid through which pressure is transmitted to the support, and means for automatically changing the pressure transmittable through the liquid to the support as the support moving means continues to act.

65. In a machine of the class described, a reciprocating breasting knife, a stop arranged to drop upon the shoe after its insertion in the machine, a wedge for holding the stop against movement, and means for thereafter operating the knife to breast the heel.

66. In a machine of the class described, a reciprocating breasting knife, a stop arranged to engage the shoe after its insertion into the machine, a wedge, means for operating the wedge to hold the stop against upward movement, means for raising the shoe against the stop, and means for thereafter operating the knife to breast the heel.

67. A heel breasting machine comprising a reciprocating knife, a work support movable toward and from the knife, a stop movable in the direction of the knife, and a wedge movable into position above the stop to render the stop fixed for arrestment of movement of the work toward the knife during the operation of the knife.

68. A heel breasting machine comprising a reciprocating knife, a work support movable toward and from the knife, a stop movable in the direction of the knife, a wedge movable into position above the stop to render the stop fixed for arrestment of movement of the work toward the knife during the operation of the knife, and means to vary the operative position of the wedge.

69. In a heel breasting machine, the combination of heel breasting means, means for locating the shoe shank relatively to the breasting means, means acting prior to said breasting means for positioning and holding said locating means, and automatic means for withdrawing the locating means after operation of the breasting means and prior to withdrawal of the shoe from the machine.

70. In a heel breasting machine, the combination of a breasting knife having a fixed limit of reciprocation, means engaging the shoe shank to locate the shoe at said limit, 5 and automatic means for withdrawing the locating means from the shoe after the shoe heel is breasted and prior to movement of the shoe.

71. A heel breasting machine comprising a cutting knife, a work support movable toward and from the knife, a stop movable relatively to the knife for limiting movement of the work toward the knife, and automatic means for withdrawing the stop 15 from the work after operation of the knife independently of movement of the support.

72. In a heel breasting machine, the combination of breasting means, a work support, a stop, and automatic means acting 20 in advance of the breasting means for causing the stop to be located in front of the heel in the proper position to prevent action of the breasting means on the shank during the action of the breasting means and for 25 causing the stop to be removed from in front of the heel before the shoe is withdrawn.

73. In a heel breasting machine, the combination of breasting means, a work support, a stop movable into position in front of the heel, means for locking the stop in the proper position to prevent action of the breasting means on the shank during the action of the breasting means, means for pressing the shoe against the stop, and means 35 for effecting relative movement between the stop and the shoe to permit withdrawal of the shoe from operative position.

74. In a heel breasting machine, the combination of a cutter having a predetermined 40 movement heightwise of the heel, means for limiting movement of the shoe heightwise of the heel with relation to the movement of the cutter, a last support initially depressible to permit positioning of a last of any 45 height beneath the cutter and against the heightwise limiting means, and means operating to exert an upward pressure on the last support.

75. In a heel breasting machine, the combination of a cutter having a predetermined 50 movement heightwise of the heel, means for limiting movement of the shoe heightwise of the heel with relation to the movement of the cutter, a last support initially depressible to permit positioning of a last of any 55 height beneath the cutter and against the heightwise limiting means, and means operating to exert a predetermined upward pressure on the last support.

76. In a heel breasting machine, a cutter having a predetermined movement heightwise of the heel, an initially depressible last support, a stop for limiting heightwise movement of the shoe toward the cutter, and power means for exerting upward pressure 65

on the last support and operating the cutter.

77. In a heel breasting machine, a cutter having a predetermined movement heightwise of the heel, an initially depressible last support, a stop for limiting heightwise movement of the shoe toward the cutter, and power means for holding the last support against depression and exerting upward pressure thereon to press the shoe against the stop. 70

78. In a machine of the class described, a cutter having a predetermined operative movement, a stop for locating a shoe in proper relation to the operative movement of the cutter, an initially yieldingly depressible last support for permitting a last of any height to be located against said stop, and means for effecting upward pressure upon the last support to hold the shoe against the stop during the operation of the cutter. 75

79. In a heel breasting machine, a breasting cutter, a last support, means for limiting movement of the shoe toward the cutter, a light spring initially sustaining the support 80 to hold a last of any height against the limiting means, and means for assuming control of the support in whatever position it has been made to assume by the introduction of the last, said means being operable to sustain 85 the support and to press the shoe against the limiting means. 90

80. In a machine of the class described, the combination of cutting means arranged for movement to operate upon a shoe bottom to 100 a predetermined vertical extent, a stop arranged to limit movement of a shoe toward the cutting means in relation to the movement of the cutting means, a yieldingly depressible last support by which the shoe is 105 held against said stop, and means locking the support against depression and applying upward pressure thereto to force the shoe against the stop. 110

81. In a heel breasting machine, the combination of a shoe support, a power operated breasting knife, a stop for locating the work with respect to the knife, means for raising the shoe support and holding the shoe 115 pressed against the stop, and means for applying power pressure to the shoe in a direction opposed to the movement of the shoe support during operation of the knife.

82. In a power machine for breasting heels, the combination of a shoe support, an upper cross-head to which the breasting knife is connected, a lower cross-head, a drive shaft arranged to extend in a direction transverse to the cross-heads, rods connecting the cross-heads, a crank on the shaft, and a connecting rod between the crank and lower cross-head. 120

83. In a power machine for breasting heels, the combination of a shoe support, cross-heads extending transversely of a shoe 130

on the support and located respectively above and below the shoe, a knife operatively connected to the upper cross-head, a power shaft extending lengthwise of the shoe, and 5 connections between the shaft and the lower cross-head and between the cross-heads to effect power operation of the knife.

84. A heel breasting machine comprising a knife having a breasting movement relatively to the heel, a shoe support movable toward and from position beneath the knife and movable toward the knife, a stop movable toward and from position to arrest the shoe when moved toward the knife, and 10 power operated means for moving the shoe support toward the stop and holding the shoe against it during operation of the knife.

85. In a machine of the class described, a 20 reciprocating head, a cutter fixed to said head, a crank permanently connected to the head for reciprocating the head between fixed limits, and a stiff spring engaged by said head only at the time when said crank 25 is approaching one of its dead centers and acting to limit uniformly the movement of the head in one direction irrespectively of

lost motion between the crank and the head.

86. In a machine of the class described, a 30 work support, a slide mounted to reciprocate toward and from the support, a cutting tool on the slide, a crank, a link connection between the crank and slide for reciprocating the slide, and means arranged to absorb the momentum of the slide acting only when the crank approaches a dead center to take up any lost motion between the link and the crank or slide and to cause the knife stroke to terminate with the throw of the crank. 35

87. In a machine of the class described, a 40 work support, a sliding head, means for positively actuating the head between predetermined limits, a knife on the head, and yielding means acting as the knife approaches its cutting limit for absorbing the 45 momentum of the head and preventing the knife from running ahead of its actuating means by reason of lost motion between the actuating means and the head positively and accurately to determine the limit of the cutting stroke of the knife.

In testimony whereof I have signed my name to this specification.

LOUIS A. CASGRAIN.
